Specification for Design.

Patented Jan. 18, 1921.

Application filed April 30, 1920. Serial No. 378,027. Term of patent 14 years.

To all whom it may concern:

Be it known that I, CARL H. BISSELL, a citizen of the United States, residing at Syracuse, in the county of Onondaga and State of New York, have invented a new, original, and ornamental Design for a Combined Fuse and Switch Block, of which the following is a specification, reference being had to the accompanying drawing, forming a part hereof, which is a face view of this combined fuse and switch block.

I claim:

The ornamental design for combined fuse and switch block, substantially as shown.

In testimony whereof, I have hereunto signed my name at Syracuse, in the county of Onondaga, and State of New York, this 27th day of April, 1920.

CARL H. BISSELL.
